UNITED STATES PATENT OFFICE

2,497,639

TWO-POSITION MOBILE POWER SAW

Leo Underwood, Bigelow, Ark.

Application October 1, 1947; Serial No. 777,189

3 Claims. (Cl. 143—43)

1

This invention relates to power-driven portable circular saws.

An object of this invention is to provide a simplified light-weight all purpose portable saw which is of rugged construction and adaptable for use in cutting underbrush, trees, stumps, clearing of right-of-way as well as being capable of trimming limbs from fallen trees, and cutting logs into desired lengths for pulp wood or ties or the like. Also in general construction work such as bridges where the saw is useful in trimming the edges of bridge floors and cutting desired lengths of heavy timber.

Another object of this invention is to provide an improved portable power driven circular saw designed to be maneuvered on rough ground and in the underbrush where logging operations are in progress, so that the saw may be easily positioned with respect to the logs to cut same at desired points without the necessity of moving the logs to level the same.

Another object of this invention is to provide a combination of features resulting in a two-position mobile saw which is readily portable, can be quickly set up in position, minimizes labor in operation and in which the saw can operate in either vertical or horizontal position.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a top plan view of the portable saw.

Figure 2 is a side elevation of the portable saw shown in Figure 1, one rear wheel being partly broken away.

Figure 3 is an enlarged cross-sectional view of a vertically adjustable pivotal lockable housing for a saw carrying frame, the section being taken as on line 3—3 of Figure 1.

Figure 4 is an enlarged cross-sectional view of the lockable housing, the section being taken as on line 4—4 of Figure 3.

Figure 5, Sheet 1, is a bottom plan view of a motor mounting, partly broken away to show threadable adjustment means for the motor.

Figure 6 is an enlarged cross-sectional view of an adjustable clamp for the saw carrying frame, the section being taken as on line 6—6 of Figure 1.

2

Figure 7 is an enlarged cross-sectional view of a mounting for the saw shaft, the section being taken as on line 7—7 of Figure 2.

Figure 8 is an enlarged fragmentary perspective view of a channel section which carries the adjustable clamp for the saw carrying frame, the channel being shown as secured to a transverse member of the vehicle frame.

Figure 9 is a perspective view of the bottom of a motor plate.

Figure 10 is a cross-sectional view of the motor mounting shown in Figure 5, the section being taken on line 10—10 of Figure 5.

Figure 11 is a cross-sectional view of a two-position housing, the section being taken as on line 11—11 of Figure 1.

In the illustrated embodiment of the invention, the numeral 10 indicates a two-wheeled vehicle comprising a substantially rectangular vehicle frame 11. The frame 11 includes parallel side members 12 having converging diagonal braces 13 which terminate in a transverse member 14.

At the rear of the frame 11, the side members 12 are connected by a transversely positioned angle member 15. Suitably connected to the frame 11 are two handles 16 which slope upwardly rearward of the frame 11 and which are connected by a transverse member 17.

The vehicle 10 includes two ground contacting rubber wheels 18 and an axle 19 supported thereby. As shown in Figure 2, the axle 19 is secured to the frame 11 by U-shaped clamps 20.

Suitably secured to the transverse member 14 is an elevating device 21 comprising an upright guide member 22 having an upright guideway 23 and having a bearing 24 whose axis is vertical at its upper end.

A threaded crank handle 25 is rotatably mounted in the bearing 24 and is held against upward or downward motion by collars 26 and transverse pins 27. As shown in Figure 4, it will be noted that the crank 25, and hence also the bearing 24 (the latter does not appear in Fig. 4) are offset from the guide member 22.

A clamp arm 29 having a threaded aperture 30 is pivotally mounted on the threaded crank handle 25 and may be swung horizontally toward the guide member 22. Bolts 32 pass through the clamp arm 29 and through the guide member 22 and have threaded nuts 33 threaded thereon. A plate 34 is mounted on the bolts 32 adjoining the inner face of the guide member 22.

The assembled parts 29, 32 and 34 form a vertically slidable lockable housing 35 designed to receive the body portion 36 of a T-shaped saw.

frame 37. The body portion 36 is of circular cross-section and contacts the plate 34 and a plate portion 38 at the free end of the clamp arm 29.

As best shown in Figs. 3 and 4, the bolts 32 support a threaded member 40 in which a crank handle 41 having a bolt extension 42 is threaded. The extension 42 provides means for forcing the clamp arm 29 in direction of the clamp plate 34 to adjustably lock the saw frame 37 in selective angular cutting positions of the saw.

As shown in Figure 8, a channel-shaped member 45 is pivotally mounted on a pivot 46 passing through the flanges 47 of the channel and seating in bearings 48 fixed to the transverse member 15 of the vehicle frame 11.

As shown in Figure 5, the channel 45 has slots 49 for an engine mount or platform 50 on which an engine 51 is suitably mounted and secured by bolts 52 (Fig. 18) on the rear part of the machine.

The rear end of the saw frame 37 is supported in a split collar or clamp 53 which is suitably fixed to the channel member 45. The collar 53 has flanges 54, (Fig. 6) one of which is threaded for engagement with a threaded portion of a crank handle 55.

It is to be noted that the body portion 36 of the saw frame 37 has a curve 39 which forms an offset front extension 36'. This curve serves to align the engine and saw pulleys while operating in either vertical or horizontal positions.

At the termination of the extension 36' is a tubular housing 57 for a shaft 58, (Fig. 7) to one end of which a pulley 59 is secured. At the other end a large diameter circular saw 60 is secured.

It is to be noted that the housing 57 is suitably fastened to the extension 36' away from the middle of the housing so as to form a short leg 61 and a long leg 62. The short leg 61 is of such reduced length to cause the saw pulley 59 to be in alignment with a drive pulley 63 on the engine shaft 64.

Connecting the pulleys 59 and 63 is a V-shaped belt 65 which, in the position shown in Figures 1 and 2, shows a partial twist. The degree of this twist is of course dependent upon the position of the plane of the saw 60 relative to the vertical. This arrangement provides a direct belt drive whereby the saw pulley 59 changes its height of operation while retaining alignment with the drive pulley.

As shown in Figure 11, the free end of the body 36 of the saw frame 37 has two arcuately spaced V-shaped or countersunk apertures 66, spaced 90 degrees apart, and that a pin 67 having a V-shaped end is pressed by a compression spring 68 to enter a selected one of these apertures according to whether the saw is in vertical or horizontal position.

The apertures 66 and the coacting pin 67 provide releasable locking means whereby the member 36 is locked in either the position shown in Fig. 11, which corresponds to the position thereof in Figs. 1 and 2 with the saw 60 horizontal, or, upon rotation of the member 36 through an arc of 90 degrees (clockwise, Fig. 11), in the position after said rotation, in which latter position the saw 60 would obviously lie in a vertical plane, not shown. A collar 69 is threaded on a tubular boss 70 on a housing 71 fixed to the channel 45. The collar 69 maintains the pin 67 and spring 68 in position. An operating handle 72 (Fig. 1) is suitably secured to the body portion 36 of the saw frame 37 and serves for rotating the saw frame when the crank handles 41 and 55 are

actuated to loosen the clamp or lockable housing 35 and the adjustable clamp 53 shown in Figure 6.

In practice, the saw 60 may be operated at ground level or elevated to a height of about eighteen inches through the use of the vertically adjustable housing shown in Figure 3 when in horizontal position.

While in vertical position, the saw may be elevated sufficiently high to trim limbs of trees.

10 At all times the saw may be changed from vertical to horizontal position without stopping the engine and without the belt losing its normal tension. The saw revolves toward the operator, thus throwing the sawdust in the opposite direction.

15 When the saw is operated as above described in horizontal position, when the housing 35 is raised, the saw is slanting. It is however possible by the addition of an attachment (not shown) to the pivot shown in Figure 8, to cause the rear end to be raised to provide level horizontal operation at above-ground level.

20 As shown in Figures 1 and 2, the rear end of the channel 45 has a transverse wall 73 having a clearance aperture in which a rod extension 74 of a crank handle 75 is freely rotatably mounted. The crank handle is held against movement from the wall 73 by a collar 76. The free end of the rod 74 is threaded and engageable with a threaded lug 77 (Fig. 9) at one end of the engine mount 50.

25 The above threaded arrangement provides means permitting adjustment whereby the engine mount or platform 50 may be moved backward or forward along the channel 45 to adjust the belt for proper tension or for the purpose of 30 relieving the torque when starting the engine.

35 As shown in Figure 9, the engine platform 50 has parallel lugs 78 spaced-apart for engagement with the flanges of the channel 45 when making belt adjustments. The platform 50 has elongated 40 through slots 79 through which engine bolts pass for securing the engine 51 to the platform 50.

45 It will thus be seen that there has been provided a portable circular saw which can be manipulated like a wheelbarrow on ground contacting wheels and approached at any angle to a fallen log regardless of the roughness of the ground. The saw can be swung over the log to saw the log from the top downwardly and by manipulating the handles 16 the angularity of the saw 60 can be 50 readily adjusted so as to take into account the angularity of the fallen log with respect to the ground.

55 In accordance with the patent statutes I have described and illustrated the preferred embodiment of my invention, but it will be understood that various changes and modifications can be made therein without departing from the spirit of the invention as defined by the appended claims.

60 I claim:

1. In a portable circular saw comprising a vehicle having two wheels and an axle supported thereby, a vehicle frame supported on said axle intermediate said wheels, said frame converging at the forward end of said vehicle and terminating in a guide member having an upright guideway, said guide member comprising a vertically rotatable threaded rod parallel with said guideway and rearward thereof, a pivotal clamp arm threaded on said rod and movable in a horizontal plane to and from said guide member, bolts passing through said clamp arm and through said guideway and carrying a clamp plate parallel with said clamp arm, an elongated saw carrying frame 70 having a circular body portion passing through and

being rotatable in said housing, means for forcing said clamp arm in the direction of said clamp plate to lock said saw frame in various selective angular cutting positions of said saw, an engine on said vehicle body having a driving pulley, a driven pulley for said saw, and a belt connecting said pulleys and movable with said driven pulley in all positions of said saw between horizontal and vertical positions.

2. In a portable circular saw comprising a vehicle having two wheels and an axle supported thereby, a vehicle frame supported on said axle intermediate said wheels, said frame converging at the forward end of said vehicle and terminating in a guide member having an upright guideway, said guide member comprising a vertically rotatable threaded rod parallel with said guideway and rearward thereof, a pivotal clamp arm threaded on said rod and movable in a horizontal plane to and from said guide member, bolts passing through said clamp arm and through said guideway and carrying a clamp plate parallel with said clamp arm, a T-shaped saw frame having short and long legs, said frame having a shaft rotatably mounted in the leg portions thereof, a circular saw mounted on said shaft at the end of said long leg, said saw frame having a body portion receivable in said housing, said body portion being of circular cross-section to permit pivotal adjustment of said saw frame and said saw about said body portion between horizontal and vertical positions while supported by said housing, means for forcing said clamp arm in the direction of said clamp plate to lock said saw frame in various selective angular cutting positions of said saw, an engine on said vehicle body having a driving pulley, a driven pulley carried by said shaft at the end of said short leg, a belt connecting said pulleys and movable with said driven pulley in all positions of said saw between horizontal and vertical positions.

3. In a portable circular saw comprising a vehicle having two wheels and an axle supported thereby, a vehicle frame supported on said axle intermediate said wheels, said frame converging at the forward end of said vehicle and terminating in a guide member having an upright guideway, said guide member comprising a vertically

rotatable threaded rod parallel with said guideway and rearward thereof, a pivotal clamp arm threaded on said rod and movable in a horizontal plane to and from said guide member, bolts passing through said clamp arm and through said guideway and carrying a clamp plate parallel with said clamp arm, a T-shaped saw frame having short and long legs, said frame having a shaft rotatably mounted in the leg portions thereof, a circular saw mounted on said shaft at the end of said long leg, said saw frame having a body portion receivable in said housing, said body portion being of circular cross-section to permit pivotal adjustment of said saw frame and said saw about said body portion between horizontal and vertical positions while supported by said housing, means for forcing said clamp arm in the direction of said clamp plate to lock said saw frame in various selective angular cutting positions of said saw, an engine on said vehicle body having a driving pulley, a driven pulley carried by said shaft at the end of said short leg, a belt connecting said pulleys and movable with said driven pulley in all positions of said saw between horizontal and vertical positions, and means for tilting said T-shaped frame upwardly in angular relation relative to said vehicle body, with the vertex of the angle positioned rearwardly of said lockable housing.

LEO UNDERWOOD.
